UNITED STATES PATENT OFFICE

AXEL F. CARLSON, OF CAMBRIDGE, MASSACHUSETTS, ASSIGNOR TO THE REECE BUTTON HOLE MACHINE COMPANY, OF BOSTON, MASSACHUSETTS, A CORPORATION OF MAINE

THREAD HOLDER AND TRIMMER FOR BUTTONHOLE SEWING MACHINES

Application filed March 21, 1928. Serial No. 263,285.

This invention relates to buttonhole sewing machines of that type which are equipped with means for cutting the under thread at the end of the buttonhole and for holding the severed end until the first stitches have been formed on the next succeeding buttonhole.

The object of the invention is to provide an improved means for thus holding the cut end of thread and subsequently releasing said end after the first stitches of the buttonhole have been formed.

In order to give an understanding of the invention I have illustrated in the drawings some selected embodiments thereof which will now be described after which the novel features will be pointed out in the appended claims.

Fig. 1 is a side view of a buttonhole sewing machine embodying my invention;

Fig. 2 is a fragmentary plan view of the work support showing the cutter for the under thread;

Fig. 3 is an under side view of the work support illustrating the thread holder;

Fig. 4 is a fragmentary edge view of the thread holder;

Fig. 5 is a view of the thread holder detached from its actuating mechanism;

Fig. 6 is a view illustrating the manner in which the thread enters the thread gripper;

Fig. 7 is a view similar to Fig. 3 showing a different embodiment of the invention;

Fig. 8 is a fragmentary view showing the thread holder in Fig. 7 opened for releasing the thread;

Fig. 9 is an enlarged section on the line 9—9, Fig. 7.

I have chosen herein to illustrate my invention as it might be embodied in the sewing machine of the type shown in my Patents #1,705,044, March 12, 1929 and #1,771,670, July 29, 1930.

Referring to Fig. 1, 1 indicates the frame of the sewing machine which is provided with the work-supporting arm 2 equipped with a clamp plate 3 on which the work is clamped by means of suitable work clamps

50 4.

The stitch-forming mechanism comprises the usual needle 5 by which the upper thread is manipulated and which is carried in a vertically-reciprocating needle bar 6 which is mounted in the overhanging arm 7 of the frame 1, and under thread mechanism which may be in the form of the usual bobbin carrying the under thread and a rotary hook associated therewith by which the upper and under thread are concatenated.

The work-supporting plate 3 is provided with the usual sewing opening or throat 8 through which the needle 5 operates.

The stitch-forming mechanism is driven by any suitable means from the driving shaft 9 which in turn is driven from the driving pulley 10 through any appropriate clutch device.

The parts which have thus been briefly referred to are or may be of any suitable or usual construction and form no part of my present invention, which relates particularly to the means for holding the end of the under thread after it has been cut at the completion of a buttonhole. When the sewing 10 on the buttonhole is completed and the machine is brought to rest by the usual stop motion, the under thread, which extends from the work to the bobbin, is cut beneath the work and close to the work. This cutting is done by means of a thread cutter 9 (see Fig. 2) which is constructed and operated similar to the thread cutter shown in my patent #1,705,044, March 12, 1929.

The thread cutter is situated above the plate 3 but operates beneath the work. It is provided at its forward end with a cutting edge 10 and is pivotally connected at its rear end as shown at 11 to a block 12 which is slidable in a guideway 13 formed in the plate 3. The cutting blade 9 has a pin 14 depending therefrom which operates in an inclined slot 15 formed in the plate 3, the construction being such that when the slide 12 is moved forwardly the cutting knife will be given both a forward movement and also a partial swinging movement thereby to carry the cutting edge 10 across the sewing opening 8. During this movement the cutting edge of the knife will engage the under thread lead- 140

ing from the work through the sewing opening and will sever the latter close to the work all as described in my above-mentioned Patent 1,705,044.

5 The means employed for operating the slide 12 and the knife 9 are similar to those shown in my co-pending applications. This slide 12 is connected to a block 16 situated on the under side of the plate 3 by suitable connections which extend through and operate in the slot 17 formed in said plate so that the slide 12 and block 16 constitute a rigid unit.

The block 16 is provided with a depending pin 18 which is adapted to be engaged by a finger 19 extending from a slide or bar 20 situated on the under side of the plate 3 and movable longitudinally of the buttonhole slit. When this slide 20 is given a movement toward the right in Fig. 1 or upwardly in Fig. 20 3 the finger 19 will engage the pin 18 and thereby give the slide 12 its operative movement to cause the cutter 9 to cut the lower thread.

This actuating slide 20 is given its operative movement upon the completion of the buttonhole by means of a cam device 21 which is normally idle during the sewing operation but is rendered operative at the completion of the buttonhole all as illustrated in my above-mentioned Patents #1,705,044 and 1,771,670.

The rear end of the slide 20 is provided with an opening through which extends the lower end of an arm 22 pivoted at 23 to the frame 1, the upper end of said arm having a slot 24 therein in which is received a pin 25 carried by an arm 26 fast on a rock shaft 27. Said shaft has fast therewith another arm 28 which bears against the cam 21 and is held in contact therewith by a suitable spring 29. With this arrangement it will be observed that when the cam 21 is given its rotation at the end of the buttonhole, in the manner described in the above-mentioned patents, the arms 28, 26 will be rocked and the lever arm 22 will be swung backwardly thereby giving backward movement to the slide 20, which backward movement will actuate the under thread cutter 9. As soon as the cam 21 has completed its movement the slide 20 will be returned to its initial position by means of a return spring 30. The cutter 9 is returned to its normal position by means of an arm 31 which is adapted to engage the pin 18 upon the return movement of the slide 20.

55 The under thread holding device with which this invention is particularly concerned, is associated with the slide 20. When the slide 20 is in its normal or forward position as shown in Fig. 3 there is considerable lost motion between the pin 18 and the finger 19 so that the slide has a certain movement before the finger 19 engages the pin 18 to actuate the cutter. The thread-gripping device 60 for the under thread is arranged so that dur- 65

ing this initial motion of the slide 20 said gripping device will engage and grip the under thread with the result that when the finger 19 comes in contact with the pin 18 to actuate the cutter the under thread is already 70 gripped between the cutter and the source of supply.

The under thread gripper shown in Fig. 3 comprises two gripping jaws 32 and 33 between which the under thread, indicated at 34, is adapted to be gripped. The jaw 32 is formed on an arm 35 which is rigid with and extends from a plate 36, the latter being adjustably secured to the slide 20. For this purpose the plate 36 is shown as having a slot 37 through which extends a guiding pin 38 extending from the slide 20 and another slot 39 which receives a clamping screw 40 carried by the slide, this construction providing for adjustment of the plate 36 longitudinally of the slide 20 thereby to provide for setting the thread-holding device properly with reference to the sewing opening and other parts of the machine.

The clamping or gripping member 33 is pivotally mounted to the other gripping member as shown at 41 and it is acted on by a spring 42 which connects it with the plate 36 and which yieldingly holds it in its operative position or closed relation with reference to the gripping jaw 32. The gripping jaw 33 is guided in its swinging movement partly by the arm 35 and partly by a guiding finger 43, said gripping member operating between the arm and the finger. 100

The parts are shown in Fig. 3 in the position they occupy at the end of the sewing on the buttonhole. When the buttonhole is completed the slide 20 is moved upwardly in Fig. 3 as above described and during the initial upward movement the gripping jaws 32, 33 are carried underneath the sewing opening 8, as shown by the dotted lines in Fig. 3. During this movement the under thread which extends through the sewing opening engages the curved edges 44 of the gripping jaws and is guided thereby between the latter, the jaw 33 swinging backwardly to allow the thread to enter between them as shown in Fig. 6, said thread finding lodgment in the notch 45 of the jaw 32. The spring 42 is a relatively light spring so that the jaws will readily open to receive the thread without placing any undue strain on the thread, the jaws being opened by the pressure of the thread thereagainst as they move from the full to the dotted line position, Fig. 3. By the time the thread has been gripped between the jaws the finger 19 will engage the pin 18 and thereby actuate the thread cutter 9, which cuts the under thread between the work and the thread gripper. 110 115 120 125

After the cutting operation has been performed the slide 20 is returned to its initial position shown in Fig. 3 as above described 130

and during its return movement the cut end of under thread 34 is held in the gripping jaws, said thread being retained in the jaws until after the stitching has begun on the next succeeding buttonhole.

10 I have provided herein means whereby as the first stitches are being formed on the next succeeding buttonhole the pivoted jaw 33 is opened positively thereby to release the end of under thread and for this purpose I have provided herein means actuated by the feeding movement of the work clamps.

15 When the sewing machine is started and after the work clamps 4 have closed onto the work said work clamps are given a feeding movement in a direction to the left Fig. 1 to cause the stitches to be formed on one side of the buttonhole and then in a reverse direction to cause the stitches to be formed along the other side of the buttonhole.

20 The work clamps are mounted on a clamp plate 46 which slides back and forth on the arm 2 to give the work its feeding movement. This plate 46 has rigid therewith an extension or abutment 47 which slides along the edge of the work-supporting arm 2 as the work clamps move back and forth. Said abutment 47 is adapted to engage a thrust bar 48 which is moved longitudinally in suitable bearings 49 carried by the work-supporting arm 2. The forward end of the thrust bar engages one end of a lever 50 which is pivoted intermediate of its ends at 51, the other end of said lever carrying a pin 52 adapted to engage a cam face 53 formed on a rearward extension of the pivoted jaw 33.

25 The lever 50 is acted on by a return spring 54 which normally holds it in the position shown in Fig. 3. From this construction it will be seen that when the thrust bar 48 is moved downwardly in Fig. 3, which will be the motion given to it by the abutment 47 as the stitching on the buttonhole begins, the lever 50 will be turned about its pivot 51 thus causing the pin 52 to engage the cam face 53 of the jaw 33 and swing the latter away from the jaw 32 thereby releasing the thread which is held between the jaws. Hence the jaws 32 and 33 are actuated at the end of the buttonhole to grip the under thread and the jaw 32 is again actuated at the beginning of the button hole to release the thread.

30 The thrust rod 48 is so mounted that it will be disconnected from the abutment 47 as soon as it has been given a sufficient movement to accomplish its function, the abutment 47 being permitted to continue its movement for the length of the buttonhole without further actuating the thrust rod 48. It will be noted that the rear end of the thrust rod 48 is pivotally mounted to a radius arm 55 which is pivotally mounted at 56 to the work-supporting arm 2. By reason of this construction as the thrust rod moves forwardly the rear end thereof will also swing

35 downwardly due to the rotative movement of the radius arm and said downward movement will withdraw the rear end of the thrust rod from engagement with the abutment 47 thus leaving the abutment free to continue its movement.

40 During such continued forward movement of the abutment over the top of the thrust rod 48 said abutment will hold the thrust rod from being retracted by the spring 54. Hence as the sewing is in progress the thrust rod will be held in its forward position so that the jaws will be held open as shown in dotted lines Fig. 5, such jaws closing automatically when the buttonhole has been completed and the abutment 47 has been carried back off from the end of the thrust rod.

45 In Figs. 7, 8 and 9 I have illustrated a slightly different embodiment of the invention. In these figures the two thread-gripping jaws are indicated at 57, 58. The jaw 57 is slidably mounted on the work plate 3 and the jaw 58 is pivotally mounted to the jaw 57 as shown at 59. The jaw 58 is formed with a slot 60 in which is received a guiding pin 61 carried by the plate 3 and said jaw is also formed with an extension 62 having a slot 63 therein in which is received another guiding screw 64 carried by the plate 3.

50 In the embodiment shown in Figs. 7, 8 and 9 the gripping jaws are situated on the opposite side of the sewing opening from what they are in Fig. 3 but they are given their operative thread-gripping movement by means of the slide 20. This is accomplished through a lever device 65 which is pivoted to the plate 3 at 66 and one end of which is formed with a notch 67 in which is received a pin 68 carried by the slide. At the other end said lever 65 is provided with a notch 69 which receives a pin 70 carried by the extension 62 of the gripping jaw 57.

55 Fig. 7 shows the parts in their normal position. During the initial movement of the slide the lever 65 will be swung from the position shown in Fig. 7 to that shown in full lines Fig. 8, this movement carrying the gripping jaws forwardly to engage the under thread.

60 The jaw 57 is formed with a thread-receiving notch 71 into which the under thread enters and as the gripper moves forward the jaw 58 is swung backwardly against the action of its spring 72 as shown in Fig. 8 so as to permit the thread to enter between the jaws. This opening movement of the jaw 58 is accomplished by a latch member 73 pivotally mounted on the plate 3 at 74 and adapted to engage the tail 75 of the jaw 58 as the jaws move forward. This operation is clearly shown in Fig. 8.

65 After the under thread has entered the notch 71 between the jaws then the open jaw 58 is released and is closed against the thread by means of the spring 72, the thread 34 be-

ing forced by the jaw 58 into the groove 76 formed between the body of the jaw 57 and the lug or extension 77 thereon as clearly seen in Fig. 9 and thereby being normally held.

5 In order to effect this release of the jaw 58 the latch 73 is formed with a lateral lug 78 which is adapted to be engaged by the pin 70 during continued swinging movement of the lever 65 which is illustrated from the full 16 to the dotted line position in Fig. 8 and which occurs as the slide 20 continues its movement. The engagement of the pin 70 with the lug 78 will swing the latch backwardly and withdraw it from the tail 75 of the jaw 18 58 thus allowing the jaw to close.

The end of the lever 65 having the notch 67 is so shaped that when the lever 65 has been carried to the dotted line position Fig. 8 thereby to release the jaw 58 the pin 68

20 will have been withdrawn from the notch 67 and during further movement of the slide 20 necessary to actuate the thread cutter 9 said pin merely slides along the face 79 of the lever 65. Upon the return movement 25 of the slide the pin 68 will enter the notch 67 and will restore the lever 65 to its initial position thereby retracting the gripping jaws which at this time hold the cut end of thread.

30 The spring 72 may be a relatively light spring and I have provided means for applying additional gripping pressure to the gripping jaws after they have gripped the under thread and when they are in their

35 normal position so that the under thread will be firmly held while the stitching begins on the next buttonhole. This additional pressure is secured through the medium of a spring 81 which encircles the stem 82 of a hook member 83. This stem is slidably mounted in bearings 84 and carries a collar 85 between which and one of the bearings 84 the spring is situated.

The tail 75 of the jaw 58 is formed with a 45 pin 86 which is adapted to engage the hook 83 when the jaws are in their retracted position shown in Fig. 7. As the jaws are carried back into this retracted position and the pin 86 engages the hook 83 the stem 82 will 50 be drawn backwardly thus placing the spring 81 under tension with the result that additional gripping force will be applied to the under thread. The release of this gripping pressure after the first stitches have been 55 formed on the buttonhole is accomplished through the medium of the thrust rod 48. In the construction shown in Fig. 7, however, this thrust rod is adapted to engage one end 60 of a lever 87 pivoted at 88 to the plate 3, the other end of said lever acting on a pin 89 carried by the slide 20. Hence, when the thrust rod 48 is given its operative movement by the abutment 47 as the stitching starts on any buttonhole, the slide 20 will 65 be given a sufficient backward movement to

cause the grippers to be moved forwardly to a point where the tail 75 will engage the latch 73 and thereby cause the opening of the jaws.

I claim.

1. In a two-thread sewing machine, the combination with a stationary frame having a head, of stitch-forming mechanism including a needle and a needle bar vertically reciprocating in said head, work-holding means carried by said frame and movable thereon relative to the stitch-forming mechanism, a cutter for cutting the under thread, a thread-gripping device, a sliding actuator mounted on the frame, means operated by the initial movement of said actuator to cause the thread-gripping device to grip the under thread and by continued movement of said actuator to cause the cutter to cut the under thread between the gripper device and the work. 70 75 80 85

2. In a two-thread sewing machine, the combination with a stationary frame having a head, of stitch-forming mechanism including a needle and a needle bar vertically reciprocating in said head, work-holding means carried by said frame and movable thereon relative to the stitch-forming mechanism, a cutter for cutting the under thread, a thread-gripping device comprising a pair of relatively-movable gripping jaws, a sliding actuator mounted on said frame and means to cause the thread-gripping device to grip the under thread during the initial movement of the actuator and the cutter to cut the thread between the gripper device and the work during continued movement of the actuator. 90 95 100

3. In a two-thread sewing machine, the combination with a stationary frame having a head, of stitch-forming mechanism including a needle and a needle bar vertically reciprocating in said head, work-holding means carried by said frame and movable thereon relative to the stitch-forming mechanism, a cutter for cutting the under thread, a thread-gripping device, a sliding actuator mounted on the frame, means to operate said actuator at the end of the buttonhole, and means to cause the thread-gripping device to grip the under thread during the initial movement of the actuator and the cutter to cut the thread between the gripper and the work during continued movement of the actuator. 110 115 120

4. In a two-thread sewing machine, the combination with a stationary frame having a head, of stitch-forming mechanism including a needle and a needle bar vertically reciprocating in said head, work-holding means carried by said frame and movable thereon relative to the stitch-forming mechanism, a cutter for cutting the under thread, a thread-gripping device, a sliding actuator mounted on the frame, means to operate said actuator at the end of the buttonhole, means to cause the thread-gripping device to grip 125 130

the under thread during the initial movement of the actuator and the cutter to cut the thread between the gripper and the work during continued movement of the actuator, and means to release the thread from the gripper after the next buttonhole has begun.

5 mounted on the frame, a thread-gripping device carried by the actuator, means to give the actuator its operative movement at the end of the buttonhole, the initial movement thereof of causing the gripping device to grip the 70 under thread and continued movement op-

10 5. In a two-thread sewing machine, the combination with a stationary frame having a head, of stitch-forming mechanism including a needle and a needle bar vertically reciprocating in said head, work-holding means carried by said frame and movable thereon relative to the stitch-forming mechanism, a cutter for cutting the under thread, a thread-gripping device comprising a pair of relatively movable gripping jaws, a sliding actuator mounted on the frame, means to operate the same at the end of the buttonhole, and means rendered operative by the initial movement of the actuator to cause the thread-gripping jaws to grip the under thread and by continued movement of the actuator to cause the cutter to cut said thread between the gripping device and the work.

15 20

25 6. In a two-thread sewing machine, the combination with a stationary frame having a head, of stitch-forming mechanism including a needle and a needle bar vertically reciprocating in said head, work-holding means carried by said frame and movable thereon relative to the stitch-forming mechanism, a cutter for cutting the under thread, a thread-gripping device comprising a pair of relatively movable gripping jaws, a sliding actuator mounted on the frame, means to operate the same at the end of the buttonhole, means rendered operative by the initial movement of the actuator to cause the thread-gripping jaws to grip the under thread and by continued movement of the actuator to cause the cutter to cut said thread between the gripping device and the work, and means to open the jaws and release the thread after the next buttonhole has begun.

45 7. In a buttonhole sewing machine, the combination with a stationary frame having a head, of stitch-forming mechanism including a needle and a needle bar vertically reciprocating in said head, work-holding means mounted on the frame for movement relative to the stitch-forming mechanism, a cutter for cutting the under thread, a thread-gripping device, a sliding actuator operated at the end of the buttonhole, means to cause the thread-gripping device to grip the under thread during the initial movement of said actuator and the cutter to cut said thread during continued movement of the actuator, and means operated by said relative movement when the
50 next buttonhole has begun to release the thread from the gripping device.

8. In a buttonhole sewing machine, the combination with a frame, of stitch-forming mechanism carried thereby, a cutter for cutting the under thread, a sliding actuator

mounted on the frame, a thread-gripping device carried by the actuator, means to give the actuator its operative movement at the end of the buttonhole, the initial movement thereof causing the gripping device to grip the 70 under thread and continued movement operating the cutter.

9. In a buttonhole sewing machine, the combination with a frame, of stitch-forming mechanism carried thereby, a cutter for cutting the under thread, a sliding actuator mounted on the frame, a thread-gripping device carried by the actuator and comprising a pair of relatively-movable gripping jaws, means to operate the actuator at the end of the buttonhole, the initial movement of the actuator causing it to grip the under thread and further movement operating the cutter. 75 80

10. In a buttonhole sewing machine, the combination with a frame, of stitch-forming mechanism carried thereby, a cutter for cutting the under thread, a sliding actuator mounted on the frame, a thread-gripping device carried by the actuator and comprising a pair of relatively-movable gripping jaws, means to operate the actuator at the end of the buttonhole, the initial movement of the actuator causing it to grip the under thread and further movement operating the cutter, and means to open the jaws and release the thread when the next buttonhole is begun. 85 90 95

11. In a buttonhole sewing machine, the combination with a frame, of stitch-forming mechanism and work-holding means carried thereby but having a relative movement, of a sliding actuator, a thread-gripping device carried by the actuator and having a pair of relatively-movable gripping jaws, means to move the actuator at the end of the button-hole and thereby cause the thread-gripping device to grip the under thread, and means to open the jaws by said relative movement when the stitching on the next buttonhole is begun. 100 105

12. In a buttonhole sewing machine, the combination with stitch-forming mechanism and work-holding means having a relative movement, of a cutter for the under thread, a sliding actuator operated at the end of the buttonhole, a thread-gripping device carried by the actuator and comprising two relatively-moving gripping jaws, initial movement of the actuator causing the thread-gripping device to grip the under thread, means to cause the cutter to cut the thread during continued movement of the actuator, and means actuated by such relative movement when the next buttonhole is began to open said jaws thereby releasing the thread. 110 115 120

In testimony whereof, I have signed my ¹²⁵ name to this specification.

AXEL F. CARLSON.
